UNITED STATES PATENT OFFICE.

FINDLEY R. PAINE, OF ALBANY, NEW YORK, ASSIGNOR TO STANDARD OIL COMPANY OF NEW YORK, OF NEW YORK, N. Y., A CORPORATION.

NOZZLE.

1,167,712.

Specification of Letters Patent. Patented Jan. 11, 1916.

Application filed August 25, 1915. Serial No. 47,277.

To all whom it may concern:

Be it known that I, FINDLEY R. PAINE, a citizen of the United States, residing at the city of Albany, in the county of Albany and 5 State of New York, have invented certain new and useful Improvements in Nozzles, of which the following is a specification.

My invention relates to nozzles, and the object of my invention is to provide a nozzle 10 particularly adapted for distributing oil or other preparations for laying the dust and renewing the surface of highways; together with such elements and combinations as are hereinafter more particularly set forth.

15 I accomplish these objects by means of the mechanism illustrated in the accompanying drawings.

Figure 1 is a plan. Fig. 2 is an end elevation. Fig. 3 is a side elevation. Fig. 4 is an 20 elevation of the end opposite that shown on Fig. 2. Fig. 5 is an end view of barrel D. Fig. 6 is a section along the lines A—A shown on Fig. 5. Fig. 7 is a section along the lines B—B shown on Fig. 5. Fig. 8 is a 25 view of the end of the barrel D which is opposite that shown in Fig. 5.

Similar letters refer to similar parts throughout the several views.

It is desirable when a fluid is to be applied 30 to a road either for the purpose of laying the dust or to mix with a material adapted to re-surface the highway, that the spray or stream should be directed in a thin sheet of fan-like formation so that it will spread immediately upon leaving the nozzle. It is 35 also desirable, especially in the use of nozzles applied to carts for the delivery of oil or other fluid to a street or highway, that there need to be little or no regulation of the 40 parts after they have once been set for the particular use to which they are to be put, because these carts are generally under the guidance and control of those who have little or no judgment in reference to the proper 45 amount of liquid that should be delivered from the orifice of the nozzle. It is desirable in the use to which this nozzle is especially applicable, that the flow of the liquid through it should be uniform and not affected in its uniformity of action by jolting or other violent, irregular and sudden motion. I have designed a simple, inexpensive, and extremely practical nozzle which may be regulated to permit of a larger or smaller 50 stream from the nozzle as desired and which

is provided with a means for locking the parts of the nozzle in such a position that the stream delivered therefrom will be uniform.

A casting E is open from end to end and 60 about midway between its ends, F—G, I place a nipple H preferably provided with interior threads "h" adapted to screw onto a pipe (not shown), leading to the reservoir of fluid. By means of a webb J secured to 65 or integral with the casting E and the nipple H, I pivot the fork K adapted to hang by gravity from the end of the casting as shown in Fig. 3 and Fig. 4, but which may be raised to the position shown by 70 dotted lines in Fig. 3. The casting E is provided in its side opposite the nipple H with a discharge opening L.

Into the casting E I place a barrel D provided at one end with a square projecting 75 hub "d," at the other end with a threaded post "e" and the squared shoulder "f" as shown in Figs. 6 and 7. The barrel D has a pair of passageways M—M passing diametrically through it from side to side and 80 separated from each other by a short distance, also a pair of passageways N—N extending diametrically through it at right angles to and intersecting the passageways M—M. The squared hub "d" is arranged so 85 that the faces forming the sides of the squared portions, which are preferably numbered 1, 2, 3, and 4 are so adjusted that the openings of the passageways M—M and N—N in each face of the barrel, are in a 90 plane parallel to the face of the corresponding side of the squared hub. Between the openings of the passageways M—M and N—N and each side of the barrel are placed discharge openings O and P respectively; 95 the discharge openings between the passageways M—M are connected by oblique passageways R—R with the passageways M—M, in a similar way discharge openings P are connected by oblique passageways S—S 100 with the passageways N—N; the oblique passageways R and S differ in size so that when the openings P register with the discharge opening L of the casting, a larger amount of fluid will pass through that discharge opening L than when one of the other openings O is in register with the discharge opening L.

There can be, and preferably are, four sizes depending upon which of the four sec- 110

tions of the barrel D is in register with the discharge opening L of the casting and, therefore, there are four adjustments that may be made regarding the size of the stream delivered by the nozzle. It is for the purpose of readily adjusting the nozzle to deliver the proper stream that I have placed on the faces of the hub the numbers 1, 2, 3, and 4 which will show to the operator which size of delivery passage ways are in register with the delivery orifice in the casting.

The fork K when in operative position rests with one of its tines on one side and one of its tines on the other side of the squared hub as shown in Fig. 4, which will prevent the barrel from rotating. But when it is desired to change the position of the barrel, in order to cause a larger or smaller delivery, the fork may be raised, and, by means of a suitable wrench the barrel may be rotated in either direction.

The size of the discharge orifice, L, and the distance between the openings of the passageways, M, M, and N, N, is such that only the discharge openings, P and O, register with the discharge opening, L; passageways, M, M, and N, N, being covered by the side of the casting adjacent to the discharge opening, L, therein. It is to be noticed, however, that the nipple, H, is large enough to permit not only the openings, P and O, but also the openings to the passageways, M and N, to register therewith. By this arrangement the oil or fluid to be discharged enters through the nipple, H, and passes into all of the passageways, but discharges therefrom through two of the passageways only, namely, those two oblique passageways which register with the discharge opening, L, in the casting when the barrel is in the desired position. The arrangement of the passageways leading to the discharge orifice in a direction oblique to the vertical axis of the casting causes the stream discharged to be of fan-like formation, very similar to the flame of a gas burner. This provides for a thin sheet, widely distributed and well adapted for the particular work for which this nozzle is es-

pecially designed. It is, of course, possible to rotate the barrel to a position where the flow is entirely shut off, by causing the discharge orifice, L, to register between the orifices, O and P, of the barrel.

What I claim as my invention and desire to secure by Letters Patent is:

1. A two-part nozzle, comprising a hollow casting provided with means for securing the same to a source of liquid supply and provided with a discharge orifice of smaller diameter than that through which the supply is received; with a barrel provided with diametric intercepting passageways therethrough and with obliquely arranged passageways extending from each pair of said diametric intercepting passageways to the exterior of the barrel; and means for holding the barrel in its rotative position in the casting, substantially as described.

2. In a nozzle, the combination of a hollow casting adapted to be secured to a source of liquid supply with a barrel adapted to be inserted into said casting, said barrel provided with two pairs of passageways extending diametrically through the barrel from side to side, the passageways of one pair intercepting the passageways of the other pair in the line of the axis of the barrel; four pairs of oblique passageways extending from each passageway of each pair to the surface of the barrel about midway between the openings of the passageways of said pairs respectively, said casting having a discharge opening adapted to register with the openings of said oblique passageways; indicating means on the exterior of the barrel for showing which of the oblique passageway openings is in register with the discharge opening in the casting; with means for locking the barrel in position in the casting.

In testimony whereof I have affixed my signature in presence of two witnesses.

FINDLEY R. PAINE.

Witnesses:

BEULAH CARLE,
FREDERICK W. CAMERON.
